JOHN F. BARKER, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

HOT-WATER HEATING SYSTEM.

1,089,813.

Specification of Letters Patent. Patented Mar. 10, 1914.

Application filed November 15, 1912. Serial No. 731,486.

To all whom it may concern:

Be it known that I, JOHN F. BARKER, a citizen of the United States of America, residing at Springfield, in the county of 5 Hampden and State of Massachusetts, have invented new and useful Improvements in Hot-Water Heating Systems, of which the following is a specification.

This invention relates to improvements in 10 hot-water heating systems, particularly of the type known as the "kitchen boiler," which is usually connected with the water-front of the range.

The present invention is designed to employ 15 this form of boiler in connection with kerosene burners or heaters that are conveniently located below the lower end of the boiler. The oil heaters referred to are known in the market as the "blue flame" 20 burner, such as are commonly used in oil stoves.

The invention, broadly, consists in placing 25 one or more of these oil or gas burners below the lower end of the boiler and providing means to cause the heated products of combustion therefrom to pass upward and around the exterior surface of the tank and within an inclosing casing that is spaced from the tank a suitable distance. This 30 inclosing casing is preferably provided with a suitable lining of some suitable non-conductor of heat, as asbestos. A vent is located at the upper end of the jacket to permit the escape of the heated products of 35 combustion. It has been found, in practice, that by inclosing a hot-water tank of the type referred to and employing three of these oil burners, a thirty gallon tank containing water at 60° F. can, in one hour's

40 time, be raised to practically 125° F. and that by employing the casing the water will remain hot for several hours, after the flame has been extinguished, the radiation of the heat contained in the water being prevented by the lined jacket already mentioned. The air space, in addition to the lined jacket, also serves to prevent radiation, as it is well known that an air space is an excellent insulator for heat or cold.

50 Referring to the drawings, Figure 1 is a front elevational view of the completed system, the lower end of the inclosing casing being broken away to show the jacket member that is spaced from the tank, its lining,

and the manner of conducting the heated 55 products of combustion from the burners upward and around the outer surface of the inclosed tank. This figure also illustrates the position of the oil burners and their connection with the supply. Fig. 2 is a trans- 60 verse sectional view of Fig. 1 on the line 2—2 and showing the arrangement of the burners with relation to the lower end of the tank. Fig. 3 is a vertical sectional view showing a gas-burner for heating a hot- 65 water tank, in which the bed-plate for supporting the tank is provided with a single opening and a hood or umbrella plate to conduct or lead away any moisture or water that may collect at the center portion of the 70 tank—the tank employed in this particular instance being a copper one in which the lower end is made convex, in the usual manner in this type of tank. Fig. 4 is a vertical sectional view showing a tank in which the 75 lower end is concave and oil burners are employed for heating the water in the tank; this form of bed-plate having several openings to allow the heated products of combustion to pass upward. Fig. 5 is a plan 80 view of the bed-plate proper shown in Fig. 3, illustrating the single opening for the gas-burner and the hood or grip-plate being shown in full lines; the supporting and spacing lugs for the tank being also shown. 85 Fig. 6 is a plan view of the bed-plate shown in Fig. 4, in which oil-burners are employed for heating the tank, and illustrating the several openings through which the heated products of combustion pass. Fig. 7 is a 90 detail view of the hood or umbrella-plate to receive the drippings from the lower end of the tank.

Referring to the drawings in detail,—*a* designates the usual hot-water tank or 95 kitchen boiler, the lower edge of which is suitably supported on a ring or base-member *b*. The legs *c*, three of which are shown, are secured to the base-plate *b*. Located below the lower end of the tank are the oil 100 burners or heaters *d* which consist of the usual blue flame or kerosene oil burners, three of which are shown, as indicated in Fig. 2. The upper ends of the chimneys *d'* of these burners terminate below the 105 lower end of the heater and fit into openings in the base-plate *b*, as shown. The heated products of combustion therefrom pass up-

ward directly into contact with the lower end of the tank *a*, where they spread out, and, in order to confine these heated products of combustion and cause them to engage the outer surface of the tank *a*, a jacket of sheet-iron or other material is located outside of and spaced from the tank. This jacket or casing member is designated by the letter *e*. The jacket is lined with some suitable non-conductor of heat, as asbestos, that is indicated at *f*. This jacket and its lining is spaced from the tank *a* a suitable distance, as already stated, which annular space is indicated at *g*. In this space the heated products of combustion from the burners *d* pass upward and around the outer surface of the tank, as indicated by the arrows shown at *h*. In order to permit the burned gases to escape from the space *g*, a vent-pipe *i* is provided in the upper end thereof, which pipe may be connected with a chimney or other outlet for the products of combustion.

The oil supply is indicated at *j*, with which is connected the equalizing tank *k* and from this extends the supply pipe *m*, permitting the oil to flow into the wick-receiving receptacles *n* of the burners. A drip-pan *o* is shown for the purpose of receiving any water of condensation that may collect or run back from the tank. Suitable valves in the pipe *m* for regulating the flow of oil therethrough are shown at *p*, and the usual wick-adjusting devices are indicated at *q*. The usual pipe connections for the tank are shown at *r*, *s*, *t*, and *u*. In order to determine the temperature of the water within the tank *a*, a thermometer may be provided, the same being shown at *v*.

Referring now to the construction shown in Fig. 3, in which the tank *a* is of the usual copper construction, the lower end is made convex, as shown at *w*. The lower end of this tank is provided with the usual threaded projection or nipple *x* by means of which the usual circulating pipe *x¹* is connected. *y* indicates a hood or umbrella-plate adapted to be screwed or attached to the nipple *x* in order to conduct or carry away any water of condensation that may collect and drip from the convex lower end of the tank. An opening *3* is formed in the bed-plate *b*, and over this opening is placed the hood *y*, as shown in Fig. 3. Cast integral with the bed-plate are the supporting lugs *4* on which the lower edge of the tank *a* rests. These lugs have bearing surfaces *4¹* and a lip *4²* to retain the tank in position on the bed-plate. These lugs serve the double purpose of supporting the tank and spacing the lower end of the same away from the bed-plate *b*, whereby the heated products of combustion from the gas-burner *5* will pass up through the opening *3* into contact with the lower end of the tank and

hood *y*. At this point, these heated products of combustion are spread out in an even manner and then pass upward into the annular passageway *6* around the tank *a*, and finally escape by means of the vent-pipe *i* shown in Fig. 1. The bed-plate *b* is also formed with a channel or annular groove *7* to receive the drippings from the tank *a*, which are directed into this groove by the hood *y*, should any occur. After the bed-plate *b* becomes heated from the burner *5*, these collected drippings will readily evaporate and pass up into the annular passageway *6* along with the heated products of combustion.

Referring to Fig. 4, in which the means for heating the tank are a series of oil-burners already referred to, the bed-plate *b* is formed with several inlet openings for the heated products of combustion from the burners *d*. These inlet openings from the oil-burners are shown in Fig. 6 in plan view, four of them being provided, as designated by the numeral *8*. In Fig. 4, the tank shown is what is known in the trade as a "galvanized iron" tank, the bottom portion of which is concave, indicated at *9*, and the edge of this tank rests upon the lugs *4*, which serve, as already described, to support the tank and space it away from the bed-plate *b*, whereby a space or passageway *10* is formed to permit the heated products of combustion to spread out at the lower end of the tank before passing upward into the annular space *11*. In this construction the drippings, or water of condensation, leave the lower end of the tank at the rim portion *12* and drop down into the channel *13*. After the bed-plate *b* becomes heated from the burners, this collected moisture is soon evaporated and carried off, as already described. The bed-plate *b* is formed with a rim *b¹*, and inside of this rim is located the sheathing or jacket *e*. The circulating pipe *14*, in the construction shown in Fig. 4, passes upward through the center of the bed-plate, as indicated. Between the grooved or depressed portion *7* and the rim or beaded edge *b¹* is a ledge portion *7¹* on which the jacket-member *e* rests, as shown.

From this construction and the accompanying description, it is evident that a convenient and inexpensive hot-water heating system from kerosene oil, and gas is provided. When oil burners are used, it can be installed, in fact, where there is not even city water under pressure, as the tank may be supplied by hand pumps, and, after the water is heated, the lamps extinguished and the heated water drawn off as wanted. Such a system could, of course, be readily installed in country residences.

It should be stated that when a plurality of burners are used, as shown in Figs. 1 and 2, and 4, a hood *y¹* is attached to the

pipe r to receive any drippings that may run down the circulating pipes x^1 or 14. The diameter of this hood is such that any drippings will be carried away from the 5 pipe so as to fall into the depressions or grooves in the bed-plate and then evaporated by the heat from the burners.

What I claim is:—

1. In a hot-water heating system, the combination with a tank for containing the water to be heated, of a bed-plate member for supporting the tank and provided with means to space the lower end of the tank from said member, the member having an 10 opening in the central bottom portion, a jacket-member surrounding and spaced from the tank to afford an annular passageway for the heated products of combustion to pass up and around the tank, said passageway 15 communicating with the space below the lower end of the tank, a burner arranged below the opening in the bed-plate to permit the products of combustion to pass upward into the space below the lower end of 20 the tank, and to cause the heated products of combustion to spread out in an even manner before they pass upward into the annular space around the tank, and an annular 25 groove formed in the bed-plate and about the burner opening to receive and retain any drippings from the tank that may occur whereby when the bed-plate becomes heated the drippings will be evaporated and pass upward with the heated products of 30 combustion, as described.

2. A bed-plate for supporting hot-water tanks, and formed with an opening in the bottom portion of the same, said portion being depressed in relation to the rim portion 40 thereof to form a channel to receive drippings from the lower end of the tank, said plate being formed with supporting lugs on the rim portion and designed to receive the lower edge of the tank and space the 45 same from the bed-plate, whereby when the heated products of combustion from a burner located below said opening pass upward therethrough they will be spread out before passing upward and around the sides 50 of the tank, and a jacket-member spaced from the side of the tank to confine the heated products of combustion, said jacket-

member resting upon the rim portion of the bed-plate, as described.

3. A hood to receive the drippings from 55 the convex lower end of a hot-water tank and comprising a convex upper surface, to direct the drippings to its outer edge, a perforated threaded connection on the hood for attaching the same to the nipple on the lower 60 end of the tank and for affording connection with a circulating pipe, as described.

4. A water-heating apparatus comprising a tank to contain the water to be heated, an inclosing shell therefor spaced from the 65 tank, a bed-plate to support the tank and formed with an opening therethrough to permit the heated products of combustion from a burner located below the openings to pass therethrough, said plate having depressions about the opening, a concavo-convex drip-plate located below the lower end of the tank with its convex side uppermost, centrally arranged about the axis of the tank, and extending over the depressed portion of the bed-plate to convey any drippings from the tank to the depressed portion of the bed-plate, whereby when the plate becomes heated the drippings will be 70 evaporated, as described. 80

5. In a water-heater, the combination with a tank or boiler to contain the water to be heated, a surrounding casing open at its upper and lower end and spaced away from said tank, a bed-plate member to support 85 the tank and casing and having an opening to receive a pipe connection, a convex drip-plate located below the lower end of the tank over the opening and extending over and beyond the edge of the opening in the bed-plate to carry the water of condensation 90 away from said opening, a burner located below the opening to heat the tank, said bed-plate being formed with a depression between the opening and its outer edge portion to receive the drippings, whereby when the bed-plate member becomes heated the water of condensation will be evaporated, 95 as described.
